US0D1044857S

(12) **United States Design Patent** (10) Patent No.: **US D1,044,857 S**
(45) Date of Patent: ** Oct. 1, 2024

(54) **DISPLAY SCREEN WITH GRAPHICAL USER INTERFACE**

(71) Applicant: **DRILLDOCS COMPANY**, Houston, TX (US)

(72) Inventors: **Francois Ruel**, Victoriaville (CA); **Martin E. Oehlbeck**, Cohocton, NY (US); **Deep Rajendrakumar Joshi**, Houston, TX (US); **Calvin Stuart Holt**, Houston, TX (US)

(73) Assignee: **DRILLDOCS COMPANY**, Houston, TX (US)

(**) Term: **15 Years**

(21) Appl. No.: **29/859,858**

(22) Filed: **Nov. 14, 2022**

(51) LOC (14) Cl. **14-04**

(52) U.S. Cl.

USPC **D14/485**

(57) **CLAIM**

The ornamental design for a display screen with graphical user interface, as shown and described.

DESCRIPTION

The sole FIGURE is a front view of a display screen with a graphical user interface showing our new design.

The large broken lines illustrate an electronic device of the environmental subject matter. The medium broken lines illustrate a display screen. The small broken lines illustrate a graphical user interface. No subject matter depicted in broken lines form part of the claimed design.

1 Claim, 1 Drawing Sheet
